Primary Examiner — Thomas Johannes*Assistant Examiner* — Shawn T Gingrich(74) *Attorney, Agent, or Firm* — Jackson Walker LLP(57) **CLAIM**

The ornamental design for a connector apparatus, as shown and described.

DESCRIPTION

FIG. 1 is a perspective view of a connector apparatus showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom view thereof; and,

FIG. 7 is a top view thereof.

The broken line portion of the figure drawings is included to show unclaimed subject matter only and forms no part of the claimed design.
